UNITED STATES PATENT OFFICE

169,027

REFRIGERATOR OR THE LIKE

Ronald M. Cleveland, Los Angeles, Calif., assignor to Rheem Manufacturing Company, Richmond,
Calif., a corporation of California

Application April 28, 1952, Serial No. 19,508

Term of patent 3½ years

(Cl. D67—3)

To all whom it may concern:

Be it known that I, Ronald M. Cleveland, a citizen of the United States, residing in Los Angeles, county of Los Angeles, State of California, have invented a new, original, and ornamental Design for a Refrigerator or the like, of which the following is a specification, reference being had to the accompanying drawing, forming part thereof.

Fig. 1 is a perspective view of a refrigerator or the like, showing my new design;

Fig. 2 is a fragmentary side elevational view of the apparatus of Fig. 1, showing particularly the handle and emblem;

Fig. 3 is a fragmentary top plan view showing particularly said handle and emblem;

Fig. 4 is a fragmentary front view showing said handle and emblem; and

Fig. 5 is a cross-sectional view on line 5—5 of Fig. 4.

The essential features of my design reside in the portions shown in full lines.

I claim:

The ornamental design for a refrigerator or the like, substantially as shown and described.

RONALD M. CLEVELAND.
